Inventor;

W. B. Twiford

UNITED STATES PATENT OFFICE.

WM. B. TWIFORD, OF CHINCOTEAGUE, VIRGINIA.

WASHING-MACHINE.

Specification of Letters Patent No. 22,756, dated January 25, 1859.

To all whom it may concern:

Be it known that I, Wm. B. Twiford, of Chincoteague, in the county of Accomac and State of Virginia, have invented a new and useful Improvement in Washing-Machines; and I do hereby declare that the following is a full, clear, and exact description of the same, reference being had to the accompanying drawings, forming a part of this specification, in which—

Figure 1, is a plan or top view of a washing machine having my improvements attached. Fig. 2, is a side view of the same. Fig. 3, is a vertical longitudinal section of the same.

Similar letters of reference, in each of the several figures indicate corresponding parts.

The nature of my invention consists in the opposing incline planes on the underside of the ends of the sliding roller frame, in combination with fixed concave projections or ledges on the sides of the tub or box, and with grooves of greater width than the diameter of the journals of the roller in the sides of the box; whereby, when the roller is moved back and forth it is caused to nearly touch the bottom of the box or tub, when it arrives at the center thereof, and to rise considerably above the bottom of the same, when it arrives at either end of the tub. By having the roller operate thus, the clothes are subjected to the greatest squeezing action when the roller is at the center of the tub and allowed to lighten up, and admit a fresh circulation of water and air through them, when the roller is at either end of the tub, and thus an alternate squeezing and lightening up operation is being carried on, as the roller is drawn back and forth, and the clothes consequently effectually washed.

To enable others, skilled in the art, to make and use my invention, I will proceed to describe its construction and operation.

A, represents the tub or box, it has a wide horizontal slot B, in each side. The top of this slot communicates at its center with a vertical slot a, which is enlarged at its upper termination so as to form an upper bearing b. On the outer sides of the box are concave ledges C, C, which serve the office of preventing the escape of water through the oblonge slots B. They also serve as guides and supports for the roller frame and as lifters or elevators of the same, as will be described. c, c, are diagonal flutes or grooves on the bottom of the tub.

D, is the roller fluted, as at g, concentric with its axis. E, the roller frame. The bearings d, d, of the roller extend through the slots B, B, and attach to the roller frame. 60

The ends of the side pieces of the roller frame are made inclined on their underside in opposite directions as shown at e, e. These inclined surfaces come in contact with the ends of the ledges C, and consequently as 65 the roller frame is moved back and forth, the roller is allowed to take the position shown in black dotted lines in Fig. 2, and caused to rise and assume the positions shown in red and blue lines in said figure. It is by 70 this change in the position of the roller that the clothes are squeezed at the center of the tub and tightened up at the ends of the same, as stated in the forepart of the specification. These changes in the position of the roller 75 are provided for by making the slots B, B, of greater width than the diameter of the journals of the roller, and said changes being effected by reason of the moving inclines coming in contact with fixed objects. By 80 referring to Fig. 3, the manner in which the roller is adjustable so as to admit clothes under it will be readily understood.

To wash clothes with this machine, the tub is supplied with water &c. and the 85 clothes placed under the roller, the roller lowered from the position shown in Fig. 3, to the position shown in Fig. 2. The operators lay hold of the ends of the frame and slide it back and forth. As it thus 90 moves, the roller partly revolves, and owing to this and the oblique position of the lower flutes, a very perfect rubbing action is obtained and the clothes washed with almost as little injury and as perfectly as by hand. 95

What I claim as my invention and desire to secure by Letters Patent, is—

The opposing incline planes e, e, on the underside of the ends of the sliding roller frame E in combination with fixed concave 100 projections or ledges C, C, on the sides of the tub or box, and with grooves B, of greater width than the diameter of the journals of the roller, in the sides of the box, substantially as and for the purposes set forth.

WM. B. TWIFORD.
